PISTON CONSTRUCTION

Newton J. Buren, Tacoma, Wash.

Application October 27, 1948, Serial No. 56,751

10 Claims. (Cl. 309—11)

1

This invention relates to pistons such as are used in the power cylinders of internal combustion engines and has special reference to improvements in the piston construction disclosed in my prior Patent No. 1,885,681, issued November 1, 1932.

As explained in said prior patent, there is much advantage in providing such pistons, which have one side of the piston slotted, with internal ribs eccentrically disposed with reference to the axis of the piston. Flexibility of the skirt causes the piston to chatter or vibrate from connecting rod forces because it is not stiff enough to resist them. This results in noisy action, loss of power through wearing the faces of the piston rings slightly rounded, resulting further in oil pumping. A flexible piston hinges opposite the slot where there is no means provided to stiffen that portion of the skirt.

Definite means for overcoming the disadvantages above set forth is found by providing eccentric ribbing of eccentric contour in cross section to offset the flexibility of the usual split skirt piston. The eccentric ribbing replaces a large amount of the rigidity lost when splitting the piston skirt. As shown in said prior patent, the eccentric ribs of the piston are disposed well away from the open end or mouth of the piston. In so disposing eccentric ribs a considerable extent of the slotted skirt is left with but little support from the eccentric rib.

The present improvement overcomes the defects in prior devices including the patented structure referred to by providing an internal centering rib concentric with the piston contour at the extreme end of the piston skirt so that the piston may be conveniently and accurately centered, while the eccentric rib instead of being well away or spaced from the concentric rib and open end or mouth of the piston, is located immediately adjacent thereto and as close to the end of the skirt as possible and merging therewith as one, not only to more effectively eliminate chatter or vibration but to permit proper centering and enhance same.

In view of the foregoing it is one important object of the invention to provide a piston construction in which an eccentric rib is so positioned as to most effectively resist chatter or vibration due to unsupported parts of the slotted portion of the skirt.

Pistons of this character are finished externally in most cases by turning on a lathe, a mandrel being inserted in the open mouth of the piston and a dead center carried by the tail stock of

2

the lathe being engaged in a suitable center hole formed in the closed end of the piston. To enable the mandrel to have a proper fit in the piston the latter is provided at its mouth with an internal rib extending around the piston concentric with the axis thereof.

Another important object of the invention is to provide an improved piston construction wherin an internal concentric rib at the mouth is merged with an eccentric so that there exists the shortest possible moment arm between the eccentric rib and the annular edge of the piston mouth.

A further important object of the invention is to provide a piston having an internal concentric rib at its mouth and having an eccentric rib merging with the concentric rib and extending toward the closed head of the piston with gradually decreasing eccentricity.

With the above and other objects in view, as 20 will be presently apparent, the invention consists in certain novel arrangements and combinations of constructional details hereinafter fully described, illustrated in the accompanying drawings and particularly claimed.

25 In the accompanying drawings like characters of reference indicate like parts in the several views and:

Figure 1 is a sectional view extending diametrically through one form of piston constructed in accordance with this invention.

30 Figure 2 is a section on the line 2—2 of Figure 1.

Figure 3 is a diametric fragmentary view through the mouth portion of a piston showing a modification of the eccentric rib arrangement.

35 Figure 4 is a similar view showing a second modification of the eccentric rib.

In the forms of the invention as illustrated in the drawings there is disclosed a piston 10 of the type usual in internal combustion engines being in the general form of a hollow cylinder having one end 11 closed and its other end open to form a mouth 12. While the piston will vary in position in accordance with the type of engine in

40 which it is used the closed end 11 will be referred to as the upper end and the mouth 12 for convenience in the description as the lower end, this being also the position shown in the drawings.

At the upper end of the piston is a plurality of 45 spaced peripheral grooves 14 for holding the usual piston rings and at one side the wall of the piston is provided with a transversely extending or elongated radial slot 15 leading inward from the lowermost groove 14. The upper part of the 50 piston is provided with a pair of oppositely dis-

3

posed internal bosses 16 provided with axially aligned openings 17 for the reception of a wrist pin. The bosses are reinforced by ribs 18 extending to the head 11 and by ribs 19 and 20 extending to the side wall of the piston. It is to be noted that the arrangement of the bosses and the ribs extending therefrom may be varied at will without departing from the essential principles of this invention.

At the mouth 12 the piston is provided with an internal rib 21 extending around the inside of the piston wall and concentric to the axis of the piston and thus concentric to the outer side face of the piston when the latter is finished. The lower hollow part of the piston forms a skirt 22. This skirt is provided with a radial slot 23 through its wall parallel to the piston axis and extending upwardly from the bottom of the piston to the slot 15, this slot 23 also extending through the ribs 19 and 21.

As shown in Figures 1 and 2, the piston is provided with an eccentric rib 24, the center of eccentricity of this rib being displaced from the axis of the piston on a line extending diametrically from the slot 23 through the axis of the piston and at a lesser distance from the slot than said axis. With the eccentricity of the rib 24 the thickest part of said rib lies diametrically opposite the slot 23. The rib 24 has its thickest part of less radial extent than the radial extent of the rib 21 so that no part of the rib 24 extends inwardly of the rib 21. Moreover the lower face extent of the rib 24 is coincident with the upper face extent of the rib 21 so that the two ribs merge.

In the form shown in Figure 3, the eccentric rib 25 is generally arranged like the rib 24 but, instead of being substantially uniform in width or depth and its upper surface merging in a substantially abrupt manner with the inner surface of the skirt 22 it merges gradually with said inner surface as along the line 26 such as on a concaved arc rising from the narrowest part of the rib 25 at slot 23 to a point diametrically opposite the slot 23.

In Figure 4 the rib 27 extends well up along the skirt 22 much wider or deeper than rib 24 but may also be of substantially uniform width or depth and in this form, as well as that of Figure 3, the widest part of the eccentric rib is diametrically opposite the slot 23 and does not extend into the open circle of the rib 21.

It will now be plain that the eccentric rib of this invention will in no way interfere with the mounting of the piston on a mandrel for finishing the outer surface of the piston. Moreover, the piston can be conveniently, effectively and accurately centered on a mandrel by reason of the concentric rib at the mouth or end of the piston skirt, while the close proximity of the eccentric rib, adjacent, contiguous or merging with and into the concentric rib as one, enhances the major elimination of chatter or vibration of the piston, rounded wearing of the rings and oil pumping.

What is claimed is:

1. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly.

2. In a hollow piston having an open mouth at one end and having a skirt extending upwardly

4

from the mouth, a rib extending concentrically of the axis at the mouth thereof, and an eccentric rib within said mouth and merging with the concentric rib, said concentric rib and skirt having a slot extending from the bottom upwardly, said eccentric rib having its widest part diametrically opposite said slot.

3. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly, said concentric rib extending throughout inwardly of the eccentric ring.

4. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly, said eccentric rib having its widest part diametrically opposite said slot, said concentric rib extending throughout inwardly of the eccentric ring.

5. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly, said eccentric rib having its upper surface merging gradually into the inner surface of the skirt.

6. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly, said eccentric rib having its widest part diametrically opposite said slot, said eccentric rib having its upper surface merging gradually into the inner surface of the skirt.

7. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly, said concentric rib extending throughout inwardly of the eccentric ring, said eccentric rib having its upper surface merging gradually into the inner surface of the skirt.

8. In a hollow piston having an open mouth at one end and having a skirt extending upwardly from the mouth, a rib extending concentrically of the axis at the mouth thereof, and an eccentric rib within said mouth and merging with the concentric rib, said concentric rib and skirt having a slot extending from the bottom upwardly, said eccentric rib having its widest part diametrically opposite said slot, said concentric rib extending throughout inwardly of the eccentric ring, said eccentric rib having its upper surface merging gradually into the inner surface of the skirt.

9. In a hollow piston having an open mouth at one end and having a skirt extending upwardly from the mouth, a rib extending concentrically of the axis at the mouth thereof, and an eccentric rib within said mouth and merg-

ing with the concentric rib as one, said concentric rib and skirt having a slot extending from the bottom upwardly at the narrowest point of the eccentric rib.

10. In a hollow piston having an open mouth at one end and having a skirt extending upwardly from the mouth, a rib extending concentrically of the axis at the mouth thereof, and an eccentric rib within said mouth and merging with the concentric rib as a single integral unit, said concentric rib and skirt having a slot extending from the bottom upwardly, said eccentric rib having its widest part diametrically opposite said slot, the thickest part of the eccentric rib being of less radial extent than the 15 radial extent of the concentric rib so that no

part of the eccentric rib extends inwardly of the concentric rib.
